COMBINED FLAME ARRESTER AND VENT
VALVE

James J. Duggan, Charleston, W. Va.

Application November 20, 1942, Serial No. 466,377

11 Claims. (Cl. 220—88)

This invention relates to a combined flame arrester and vent valve for venting pressure vessels or systems containing ignitable fluids. In vessels containing gases and vaporizable fluids, undesirable pressures are apt to develop therein. Consequently such vessels are provided with valve controlled breather or vent devices to relieve pressures in excess of a predetermined maximum. Such devices operate satisfactorily when the vessel contains a non-combustible fluid, but when the fluids are ignitable it is the practice to provide the vent or breather opening with a fire stop to prevent the contents of the vessel from igniting by external flame sources, for example when a fire occurs exteriorly of the vessel. Such fire stops or arresters are usually composed of a screen bank which forms a multiplicity of small openings through which a flame must find ingress into the vessel so that the flame contacts the screen in such a manner that the heat of combustion is radiated with sufficient rapidity that the vapors on the inner side of the screen cannot reach ignition temperature. These banks afford relief of ordinary working pressures, but upon sudden rise in pressure they restrict the vents to such an extent that it is impossible to relieve the pressure in time to avoid injury of the vessel or explosion thereof.

It is, therefore, a principal object of the present invention to provide a flame arrester and vent valve wherein the flame arrester bank is loosely mounted in cooperating relation with the valving element and which is movable from its seat to effect rapid release of excessive pressures when those pressures cannot be relieved through the bank with sufficient rapidity to avoid injury of the vessel.

It is also a further object of the invention to provide a structure wherein the flame arrester bank is completely removable by excessive pressure to give full flow capacity of the vent or breather opening in which the bank is mounted.

Other objects of the invention are to provide a combined flame arrester and vent valve particularly adapted for venting low pressures; to provide a combined flame arrester and vent valve of simple, inexpensive construction; and to provide a combined flame arrester which, in the larger sizes, may be utilized as a manhole when the cover and fire stop unit are removed therefrom.

A sudden vacuum created in a vessel may not be relieved with sufficient rapidity through the flame arrester since the many small passes necessary to form an efficient fire stop may resist

flow of exterior pressure into the vessel in time to avoid injury to the vessel. It is, therefore, a further object of the invention to provide a combined flame arrester and vent valve with primary and secondary vacuum relief valves, the primary valve functioning at slight vacuum condition, to relieve the vessel through the flame arrester, and the secondary valve functioning to relieve the vessel independently of the flame arrester.

10 In accomplishing these and other objects of the invention, I have provided improved structure, the preferred form of which is illustrated in the accompanying drawings, wherein:

15 Fig. 1 is a vertical section through a combined flame arrester and vent valve embodying the features of the present invention.

20 Fig. 2 is a plan view of the combined flame arrester and vent valve showing the cover or valving element and other parts partially broken away to better illustrate the construction.

25 Fig. 3 is an elevational view of the flame arrester and vent valve.

30 Fig. 4 is a vertical section similar to Fig. 1 but showing the valving element and flame arrester bank in positions for venting excessively high pressures.

35 Fig. 5 is a vertical section through a modified form of the invention to afford primary and secondary vacuum relief.

40 Fig. 6 is a partial horizontal section on the line 6—6, Fig. 5.

45 Referring more in detail to the drawings:

45 I designates a combined flame arrester and vent valve embodying the features of the present invention and which includes a body 2 having an upper cylindrical wall portion 3 and a lower cone portion 4 terminating in a flange 5 that is suitably attached to the wall of a closed vessel 6, through a suitable fitting 6', by fastening devices such as cap-screws 7. The upper part of the wall portion 3 terminates in an outwardly and upwardly flaring flange 8 which provides an internal annular beveled shoulder or seat 9 and an encircling lip forming a valve seat 10.

50 The wall portion 3 forms a compartment 11 of a size to contain a fire stop, such as a flame arrester bank 12, having a sufficient number of openings 13 so that the combined flow capacity thereof may be equal to or in excess of the normal flow capacity of the inlet opening 14 of the body 2 that registers with an opening 15 of the vessel 6. The compartment 11 is also of a size relative to the flame arrester bank so as to 55 provide an annular by-pass 16 between the cir-

cumferential wall 17 of the bank and the inner face of the wall 3 for a purpose later described.

The upper portion of the body 2 is ordinarily closed by a cover or vent valve element 18 to retain a predetermined maximum working pressure in the vessel 6 but which is movable from covering relation to allow release of pressure in excess of the predetermined maximum. The cover 18 preferably includes a cap-like body having a top 18' of larger diameter than the lip 10 so that an annular depending flange 19 at the marginal edge of the top 18' is spaced a sufficient distance from the lip 10 to provide an annular outlet passageway 20 and to accommodate a flexible valving ring member or annulus 21.

In the illustrated instance the cover is pivotally connected at one side thereof with the body 2 by a hinge 22 comprising outwardly extending ears 23 and 24 on the portion 3 of the body 2 and ears 25 and 26 depending from the flange 19 and which are connected with the ears 23 and 24 by a hinge rod 27 passing through suitable openings in the respective ears. The opposite side of the cover is supported in proper relation with the lip 10 by means of an outwardly extending lug 28 which carries a resilient button 29 seating the cover, as best shown in Fig. 1.

The flexible valving ring 21 has its outer marginal edge 30 clamped between a ring 31 fixed to the inner face of the flange 19 and a removable ring 32 that is secured to the fixed ring by fastening devices, such as screws 33, extending through suitable openings in the removable ring, through registering openings in the flexible ring, and into threaded openings in the fixed ring, as shown in Fig. 2. The inner marginal edge of the flexible ring rests upon the seat or lip 10 and thus cooperates with the cover to close the passageway 20 from the inner flow passageway formed by the compartment 11 and the lower portion of the body 2 so as to retain normal working pressures within the vessel 6. The valving ring is yieldingly retained on the seat 10 by a ring-shaped weight 34 adapted to seat upon the ring in outwardly spaced relation with the seat 10, as shown in Fig. 1, the weight being retained in guided relation with the cover 18 by an outwardly spaced guide ring 35 that is connected with the weight ring by arms 36 which engage guide ribs 37 projecting inwardly from the flange 19. In order to support the flexible valving ring circumferentially of the seat 10, the clamping ring 32 may be provided with inwardly extending arms 38 carrying a supporting ring 39 spaced slightly from the flange 30.

The fire stop or flame arrester bank previously mentioned may be of any standard construction and is suspendedly supported within the compartment 11 by means of an annular, bell-shaped flange 40 of sufficient diameter to extend across the passageway 16 with its rim 41 engaging the seat 9 so as to normally close the outlet end of the annular passageway 16.

It is thus obvious that normal working pressures must pass through the openings of the flame arrester bank so that they act upon the inner face of the cover top 18'. When the working pressure rises above a predetermined maximum, as governed by the weight of the cover, the cover is raised thereby to effect lifting of the inner marginal edge of the flexible ring from sealing contact with the lip 10 so as to allow discharge of the excessive pressure to atmosphere through the annular passageway 20. When the pressures increase so rapidly that they cannot be adequately

relieved through the openings of the flame arrester bank, the increased pressure, acting on the under side of the flange 40 and the bottom of the bank, bodily lifts the flame arrester so that the pressure is passed between the flange 40 and its seat.

Attention is directed to the fact that the inner marginal edge of the flexible sealing ring preferably overlies the marginal edge of the flange 40 so that upward movement of the flame arrester bank, responsive to sudden rise in pressure, causes the flange to engage the projecting portion of the ring and effect positive unseating thereof.

In order that the flame arrester bank may be unseated at a predetermined pressure relative to 15 or independently of the cover, the flame arrester bank is contacted by an arm 42 projecting inwardly of the portion 4 of the body 2, and which has a curved end 43 bearing against a button 44 on the bottom of the bank. The arm 42 is fixed on a shaft 45 which is rotatably mounted in suitable bearings in an outward extension 46 of the body 2. One end of the shaft projects through a stuffing box 47 on the extension 46 and carries an arm 48 which projects from the shaft in an 25 opposite direction to the arm 42 and carries a weight 49 movable thereon whereby the effective leverage acting on the arrester bank may be adjusted by sliding the weight along the arm 48 in the manner of a poise on a scale beam.

In order to guide the flame arrester bank during movement thereof, the wall of the compartment 11 may be provided with a series of inwardly extending guide ribs 50 which loosely engage the wall 17 of the flame arrester bank, as 30 best shown in Figs. 1 and 2.

Assuming that the combined flame arrester and vent valve constructed and assembled as described is mounted on a vessel 6 and that normal working pressures are carried in the vessel, such pressures are not sufficient to effect unseating of the 40 cover or flexible valving ring. However, should the working pressures exceed the predetermined amount, they act through the openings of the flame arrester upon the cover 18' and effect lifting thereof so that the flexible valving ring is raised from the seat 10 to allow release of the 45 excess pressure.

The vent valve also functions in case the pressures in the tank should drop below a predetermined minimum, for example when emptying the 50 contents of the vessel. This is effected by atmospheric pressure acting on the under side of the flexible ring to lift the ring from contact with the seat 10 and allow exterior air to enter the vessel 55 only through the openings in the flame arrester bank. Should any flame be present when the cover is lifted, or the flexible valving ring unseated, the flame, to enter the vessel, must pass through the openings of the flame arrester, and 60 since the flame arrester is designed to disperse the heat of combustion, the combustible vapors below the flame arrester are not raised to ignition temperature. In addition to ability of the fire stop unit to dissipate heat of combustion by radiation, the small passages increase the velocity of vapors 65 passing therethrough to a point above the rate of flame propagation. In other words, velocity of vapor passing through the multiplicity of small openings or through the by-pass, when the arrester bank is lifted due to increased pressure, is increased to the point where the velocity of the escaping vapor is faster than a flame can propagate in the direction of the tank. Therefore the flame arrester protects the tank from fire hazard 70 under ordinary operation of the valving elements.

Should pressure in the vessel rise above the point at which adequate relief cannot be effected through openings in the flame arrester bank, the pressure acting thereon and against the under side of the supporting flange 40 lifts the bank so that the pressure is by-passed therearound. If the pressure should continue to rise, the flame arrester bank, being completely removable, may be blown by the pressure from the compartment, lifting the cover, and thereby completely opening the outlet through the body 2.

Attention is directed to the fact that the larger of the devices may serve the purpose of a man-hole for the vessels on which they may be installed. Upon opening of the cover and removal of the fire stop unit the passageway therethrough is sufficiently clear of obstruction to afford access into the interior of the vessel.

Under some conditions a dangerously high vacuum may be caused to occur in a vessel for the reason that air cannot pass through the fire stop unit with sufficient velocity to prevent high vacuums. This is obvious since with the structure illustrated, the fire stop unit retains its seat under such conditions.

Therefore the modified structure is equipped with a secondary vacuum relief which becomes effective when the primary relief, or that effected by way of the valve 21 and passages 13, is not adequate to protect the vessel. In this form, the body member 55 is of slightly different shape between the cylindrical wall portion 56 and the base portion 57 that attaches to the tank or vessel to be protected than the portion 4 of the body member 2 of the first described form so as to provide a substantially horizontal offset 58 circumferentially of the portion 57 and below the flame arrester bank or fire stop unit 59. Provided in this offset is a substantially annular port 60 which connects the interior of the vessel with atmosphere and through which air may enter the vessel independently of the fire stop unit 59 when adequate relief cannot be effected therethrough by way of the primary inlet port 61, under control of the primary valve 62. The valve 62, weight 63 therefor, and cover 64 are of identically the same construction and function in accordance with the corresponding parts of the first described form of invention. In order that the port 60 may be substantially continuous, the upper portion of the body is connected to the lower portion by webs

65. The secondary port is normally closed by an annular valving ring 66 also preferably formed of flexible material and having its inner and outer edges 67 and 68 supported on annular seats 69 and 70. The valving ring is supported in valving position by a metal ring 71 which is carried by spring arms 72, the spring arms having outer ends anchored to lugs 73 on the inner wall of the body member by screws 74 and the inner ends are secured to the rings 66 and 71 by fastening devices such as bolts 75. The arms 72 are designed to retain the valving ring seated under pressure differentials which may be adequately relieved by the primary valve 62 through the fire stop unit 59 but when the vacuum increases the arms 72 yield to unseat the valving ring 66 and provide secondary relief independently of the passages through the fire stop unit, thereby assuring safety of the tank when excessively high vacuums tend to occur.

From the foregoing it is obvious that I have provided a flame arrester and vent valve which protects a vessel or pressure system from excessive internal and external pressure differentials, and

which also protects contents of the vessel from ignition hazards. It is also obvious that I have provided a simple and inexpensive structure which is positive in operation, and which is adapted to low pressure vessels or systems.

What I claim and desire to secure by Letters Patent is:

1. A combined flame arrester and vent valve including, a body member having a flow passageway, a pressure vent valve cooperating with the body member to close said passageway and unsatable under a predetermined pressure to relieve pressure through the passageway, a fire stop unit loosely mounted in said passageway, a by-pass connected with the passageway and extending around the fire stop unit, and means on the fire stop unit normally closing said by-pass, said unit being shiftable responsive to pressure greater than said predetermined pressure to discharge the greater pressure through said by-pass upon opening of the relief valve.
2. A combined flame arrester and vent valve including, a body member having a flow passageway and a seat encircling said passageway, a pressure vent valve cooperating with the body member to close said passageway and adapted to open under a predetermined pressure to relieve pressure through the passageway, a fire stop unit in said passageway and spaced from the body member to form a passageway therearound, and a flange encircling the fire stop unit and engaging said seat to close the by-pass, said unit being shiftable by pressure in excess of the predetermined pressure to move said flange from seating position to by-pass said excess pressure when the vent valve is open.
3. A combined flame arrester and vent valve including, a body member having a flow passageway, seats encircling said passageway, a pressure vent valve cooperating with the body member and engaging one of said seats to close said passageway and adapted to open under a predetermined pressure to relieve pressure through the passageway, a fire stop unit in said passageway and spaced from the body member to form a passageway therearound, and a flange encircling the fire stop unit and engaging said other seat to close the by-pass, said unit being shiftable by pressure to move said flange from seating position for bypassing said excess pressure when the vent valve is open.
4. A device of the character described including, a body member having a fire stop compartment, a valve seat encircling the compartment, a fire stop seat in said compartment, a fire stop unit in said compartment having a peripheral portion engaging said fire stop seat, a flexible annulus having its inner marginal edge supported on the valve seat, a cover for said compartment, means for securing the outer marginal edge of said annulus with the cover around the periphery thereof, and means movably mounting the cover on the body member.
5. A device of the character described including, a body member having a fire stop compartment, a valve seat encircling the compartment, a fire stop seat in said compartment, a fire stop unit in said compartment having a peripheral portion engaging said fire stop seat, a flexible annulus having its inner marginal edge supported on the valve seat, a cover for said compartment, means for securing the outer marginal edge of said annulus to the cover around the periphery thereof, and means hinging the cover on the body member.
6. A device of the character described includ-

ing, a body member having a fire stop compartment, a valve seat encircling the compartment, a fire stop seat, a fire stop unit in said compartment having a peripheral portion engaging said fire stop seat, an annulus having its inner marginal edge supported on the valve seat, a cover for said compartment, means for securing the outer marginal edge of said annulus to the cover around the periphery thereof, means movably supporting the cover on the body member, and means in the body member for exerting a lifting leverage on the fire stop unit.

7. In a combined flame arrester and vent valve, a body member having a flow passageway adapted to be connected at one end to a vessel, a fire stop unit loosely contained in said passageway to form a by-pass therearound, means on said unit and engaging the body member to normally close the by-pass, a cover for said passageway and cooperating with the body member to provide a port therebetween, a relief valve normally closing said port and yieldable to provide primary relief of said vessel through the fire stop unit, said flow passageway having a secondary relief port on the vessel side of said fire stop unit, and a secondary valve controlling said secondary relief port for relieving the vessel independently of said fire stop unit.

8. In a combined flame arrester and vent valve, a body member having a flow passageway adapted to be connected at one end to a vessel, a fire stop unit loosely contained in said passageway to form a by-pass therearound, means on said unit and engaging the body member to normally close the by-pass, a cover for said passageway and cooperating with the body member to provide a port therebetween, a relief valve normally closing said port and yieldable to provide primary relief of said vessel through the fire stop unit, said flow passageway having a secondary relief port on the vessel side of said fire stop unit, and a secondary valve controlling said secondary relief port for relieving the vessel independently of said fire stop unit, said primary relief valve being set to operate at a lower pressure differential than the secondary relief valve.

9. In a combined flame arrester and vent valve, a body member having a flow passageway through which fluid is adapted to flow in either direction in said passageway, a vent valve normally closing flow through said passageway, a fire stop unit in said passageway, and cooperating means on the body member and on said fire stop unit to support said unit in one flow direction through the passageway, said fire stop unit being movable in the other direction of flow through the passageway responsive to pressure acting on the fire stop unit in excess of pressure required to actuate the vent valve.

10. In a combined flame arrester and vent valve, a body member having a flow passageway, a pressure vent valve cooperating with the body member to close said passageway and unseatable under a predetermined pressure to relieve pressure through said passageway, a fire stop unit in said passageway and smaller in diameter than said passageway to provide a by-pass around said fire stop unit, means on the fire stop unit for closing flow through said by-pass, and means in said passageway providing a support for said fire stop unit, said fire stop unit being movable from said supporting means to open said by-pass when the pressure vent valve is opened in excess of said predetermined pressure.

11. In a combined flame arrester and vent valve, a body member having a flow passageway through which fluid is adapted to flow in either direction in said passageway, a fire stop unit in said passageway, a vent valve normally closing flow through the passageway and located on one side of the fire stop unit, cooperating means on the body member and said fire stop unit to seat said unit in one flow direction through the passageway, said fire stop unit being movable in the other direction of flow through the passageway responsive to pressure acting on the fire stop unit in excess of pressure required to actuate the vent valve, and a second vent valve on the opposite side of the fire stop unit for relieving flow through the fire stop unit when the fire stop unit is seated in said passageway.

JAMES J. DUGGAN.
